(57) **CLAIM**

I claim the ornamental design for an animal trap, as shown and described.

DESCRIPTION

FIG. 1 is a top, front, and right perspective view of an animal trap showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof; and,

FIG. 7 is a bottom plan view.

The broken line showing of portions of the animal trap is included for the purpose of illustrating environmental structure only and forms no part of the claimed design.
